UNITED STATES PATENT OFFICE.

LEE DE FOREST, OF NEW YORK, N. Y., ASSIGNOR, BY MESNE ASSIGNMENTS, TO DE FOREST PHONOFILM CORPORATION, OF JERSEY CITY, NEW JERSEY, A CORPORATION OF DELAWARE.

SOUND PRODUCER.

Application filed August 20, 1918. Serial No. 250,718.

To all whom it may concern:

Be it known that I, LEE DE FOREST, a citizen of the United States, residing at New York, county and State of New York, have made a new and useful invention in Sound Producers, of which the following is a specification.

This invention relates to novel and efficient means for producing sound.

10 The object of the invention is to produce means for producing sound which will eliminate the necessity of the use of diaphragms such as are employed in transmission of sound.

15 A further object of the invention is to provide means for producing a true undistorted sound.

Further objects of the invention will appear more fully hereinafter.

20 The invention consists substantially in the construction, combination, location, and relative arrangement of parts, all as will be more fully hereinafter set forth, as shown by the accompanying drawings and finally 25 pointed out in the appended claims.

Referring to the drawings:

Fig. 1 is a view in elevation, largely diagrammatic, of a second producer constructed in accordance with my invention.

30 Fig. 2 is a sectional view taken on the line 2, 2, Fig. 1, looking in the direction of the arrows.

35 Fig. 3 is an enlarged detail section showing diagrammatically the arrangement of wires employed in accordance with my invention.

40 Fig. 4 is a transverse sectional view of a slightly modified construction employed in accordance with my invention.

45 Fig. 5 is a longitudinal sectional view of the same.

Fig. 6 is a longitudinal sectional view of a still further modified construction embodying my invention.

45 Fig. 7 is a diagrammatic view showing the manner of use of the sound producer constructed in accordance with my invention.

50 Fig. 8 is a view partially in section in side elevation of a still further modified construction embodying my invention.

Fig. 9 is a similar view of a further modified construction embodying my invention.

55 Fig. 10 is a view in side elevation, partially sectional, of a modified structure embodying my invention.

Fig. 11 is a sectional view taken on the line 11, 11, Fig. 10, and looking in the direction of the arrows.

The same part is designated by the same reference character wherever the same occurs 60 throughout the several views.

It is an established scientific fact that the expansion and contraction of a body emits sound waves, which, if the body be of a non-metallic substance, will be more nearly 65 free from distortion than is observed when metallic diaphragms are used. It is among the special purposes of my present invention to secure the expansion and contraction of a body of non-metallic character to produce 70 undistorted sound waves and to control the expansion and contraction of said body in any suitable manner, for example, by an electric current flowing through wires positioned suitably relative to the expandible 75 body and supplied with current from a suitable current source for the production of the sound.

My invention is based upon well established principles of electricity, but due to the 80 fact that the apparatus constructed in accordance with my invention necessarily employs fine wires in great length, it has been necessary, to make a disclosure on the drawings which is capable of ready interpretation when taken in connection with the following description, to distort the showing of such apparatus principally in regard to the proportion of the parts shown, and I therefore wish it to be understood that such disproportionate disclosure is made with full 85 knowledge that it is disproportionate and merely as an aid to the description and understanding of the invention obtained 90 therefrom. In accordance with my invention I employ a pneumatic ball or sphere, or other shaped body adapted to be supplied with suitable fluid, such for example, as air, through the valve 2, Fig. 1, the construction 95 of which is immaterial, and consequently 100 diagrammatically illustrated as an ordinary pneumatic tire valve, which valve is secured to the neck of the ball, sphere or other shaped body 1 to render the same airtight. If desired, and as shown, the portion of the 105 body 1 opposite to the valve 2 may be slightly extended for a purpose which will be apparent later in the description. The inflatable body 1 is wound meridionally with a fine copper insulated wire between the valve 110

end of the inflatable body 1 and the projecting end 3 so that each wire extending around the body 1 is of opposite polarity to the next adjacent wire on the body as diagrammatically illustrated in Fig. 3. The wires may be of single depth or in layers according to the size of the sphere, size of the wire, the strength of the tone desired to be produced, and the material of the wire. The wires 10 lying side by side being of opposite polarity tend to repel each other when current is flowing therethrough thereby causing a slight expansion of the wires relative to the inflated body 1, the pressure within which 15 causes the body to expand. The minute the current ceases flowing through the wires, the wires tend to assume their normal position causing the inflated body 1 to contract to its normal position.

20 In Figs. 4 and 5 I show a slightly modified construction wherein a small metal body, for example, an iron or steel core indicated at 5 is supported in a suspended position within the inflatable body 1. This core is preferably 25 in the form of a permanent magnet, with the south pole indicated at 6 and the north pole indicated at 7. The effect of the permanent magnet within the rubber ball or inflatable body 1 is to strengthen the magnetic force of 30 the wire in causing the expansion and contraction of the rubber sphere 1 due to the controlling current in the wire as will be apparent.

35 In Fig. 6 I show a still further modified construction embodying the principles of my invention wherein the wire 8 from the source is grounded to the valve stem 2, which valve stem 2 carries the mush-room magnet body 6' with the core 7' thereof of relatively small 40 diameter. The other terminal 9 of the wire is led through the tube 2 and is wound around the core 7' of the magnet 6'. On the outer surface of the rubber sphere are cemented a large number of short fine iron 45 wires forming the armature for this magnet as shown in Fig. 6. It will be noted that these wires are confined practically entirely to the equatorial space of the magnetic field. The effect of the current passing through the 50 wire 8 is to cause an equatorial contraction of the rubber sphere 1, which again assumes its normal position due to its natural elasticity and resiliency as soon as the current ceases to flow through the wire 8, 9.

55 In Fig. 8 I show a somewhat similar construction but wherein the wire is wound equatorially or laterally around the exterior of the rubber or inflatable container 1 in the form of a spiral coil, the leads of the wire in 60 this instance are illustrated as being connected to one coil of a transformer 13, the other coil of which is connected to a suitable source of current 14 and the sound source, which, for the purpose of illustration, may 65 be a microphone indicated at 15. In this

form of construction when current flows through the wire there is a contractive effect similar to the contraction of a coiled helix included in circuit with a current source. This effect is enhanced by the magnetic 70 action on the iron sphere (or permanent steel magnet) enclosed within the bulb. When the current supply is cut off or reduced, the bulb resumes its normal expanded condition, due to the expansive action of the air compressed within the same.

In Fig. 9 the construction is similar except that the wire instead of being wound equatorially or laterally is wound meridionally or vertically with adjacent wires of like 80 polarity. This effects contraction of the bulb or container upon the completion of the circuit through the wire.

In Fig. 10 the inflatable body indicated generally at 20 is in the form of a cylinder 85 to which is secured a plurality of iron wires or strips 21 in any suitable manner, for example, cemented, or vulcanized to the exterior surface thereof and extending longitudinally the cylindrical portion thereof. 90 These iron strips 21 are slightly separated from each other and are in the form of laminations. The cylinder is surrounded by a magnet 23 likewise in cylindrical form with inwardly turning flanges 24, which 95 flanges constitute the respective poles of the magnet. Wound on the inside of the magnet 23 is the iron wire 25 in the form of a coil. An annular space indicated at 26 is left between the magnet poles and the coil 100 and the periphery of the inflatable cylinder 20 to allow ample egress of sound waves set up in the air in this space due to the vibration of the cylindrical bag. Air or other fluid is admitted to the bag through either 105 of the necks thereof as will be apparent. When current is caused to flow through the coil 25 an attraction is created between the magnetic cylinder 23 and the laminations 21 secured to the exterior peripheral surface 110 of the bag 20, thereby causing an expansion of the same. As the current through the wire 25 is varied the vibrations thus secured by the expansion and contraction of the bag 115 create corresponding sound waves. In Fig. 7 I show one manner of utilizing the construction of my invention wherein the vibrating sphere is diagrammatically illustrated at 50, as located at the focus of the parabolic horn 51 so that the sound waves from the device 50 are radiated from the parabolic horn in a concentrated unidirectional manner well known in the art. Many further modified forms and constructions 120 may readily occur to those skilled in the art without departing from the spirit and scope of my invention, and I have therefore not attempted to show or describe the many different constructions capable of operating in 125 the manner heretofore described to produce 130

the results sought, and I therefore desire the foregoing description to be interpreted in an illustrative sense rather than a limiting sense. With sounders constructed in accordance with my invention it is possible to obtain true sounds free from distortion due to mechanical movements as it is apparent that the basic source of sound is from a fluid such as air set in vibration electrically and in effect cushioned on air to eliminate any possible distortion arising through vibrations set up mechanically or by any vibrating member held in metallic contact at any portion thereof.

Having now set forth the objects and nature of my invention, and having shown and described various embodiments thereof, what I claim as new and useful and of my own invention and desire to secure by Letters Patent is:—

1. The combination with an elastic air filled container, of electric wires, and means for expanding and contracting said container in accordance with the current flowing through said wires.
2. The combination with an elastic air filled container, a metallic core suspended in said container, and electric wires wound around the exterior of said container.
3. The combination with a hollow rubber container sealed with air therein, of a metal body suspended in said container, of means

cooperating with said metal body for causing said container to expand and contract.

4. The combination with a hollow rubber container sealed with air therein, of a metal body suspended in said container, of wires wound around said container.

5. The combination with a hollow rubber container sealed with air therein, of a metal body suspended in said container, of electrically controlled means cooperating with said metal body for causing said container to expand and contract.

6. Means for generating sound waves comprising a sealed inflated elastic body, wires wound around the exterior surface of said body, and means for controlling the current through said wires by and in accordance with the sound to be produced to thereby expand and contract said body as and for the purpose described.

7. Means for generating sound waves comprising a sealed inflated elastic body, wires wound laterally around the exterior surface of said body, and means for controlling the current through said wires by and in accordance with the sound to be produced to thereby expand and contract said body as and for the purpose described.

In testimony whereof I have hereunto set my hand on this 8th day of August A. D. 1918.

LEE DE FOREST.
